CARD DISPLAY HOLDER

Kathi Urbach Sperling, New York, N. Y.

Application July 20, 1954, Serial No. 31,511

Term of patent 14 years

(Cl. D80—10)

FIG. 1.

To all whom it may concern:

Be it known that I, Kathi Urbach Sperling, a citizen of the United States, residing at New York, county of New York, State of New York, have invented a new, original, and ornamental Design for Card Display Holder, of which the following is a specification, reference being had to the accompanying drawing, forming a part thereof, and wherein:

I claim:

The ornamental design for a card display holder, substantially as shown.
